UNITED STATES PATENT OFFICE

2,516,173

ROAD MARKER

Frank E. Ballew, Woodland, Mich.

Application April 22, 1946, Serial No. 663,848

10 Claims. (Cl. 91—12)

1 This invention relates to road marking equipment and refers more particularly to apparatus for applying stripes or colored lines on the road surface.

The method directing vehicle traffic on highways by the use of colored lines or stripes on the surfaces of highways to divide the latter into separate lanes has been more or less universally adopted and contributes materially to reducing accidents. One method of striping highway surfaces which has proved especially effective and is the most economical from a material point of view is to separate oppositely moving lanes of traffic by applying a broken line on the road surface.

Although the above procedure is highly effective and is specified in many localities, nevertheless, it introduces the problem of uniformly applying the line so that the length of the spaces bear some relationship to the length of the painted portions of the line. It is one of the objects of this invention to overcome the above problem by periodically operating the coating applying means in timed relation to the rate of travel of the equipment along the road surface.

Another object of this invention is to provide timing apparatus operatively connecting a ground engaging wheel of the equipment to the coating applying means for starting and stopping operation of the coating applying means at predetermined intervals.

A further object of this invention is to provide means for adjusting the timing mechanism to vary the lengths of the painted and blank portions of the broken line.

Still another object of this invention is to provide means for adjusting the timing mechanism to vary the relative lengths of the painted and blank portions of the broken line. This adjustment in combination with the one set forth in the preceding paragraph renders it possible to apply practically any specified type of broken line on the surface of the highway.

A still further feature of this invention is to provide the timing mechanism with additional adjusting means which enables starting the painting cycle at any preselected location on the road surface. This feature is especially important in instances where it is desired to retrace previously applied broken lines on the road surface.

The foregoing as well as other objects will be made more apparent as this description proceeds, especially when considered in connection with the accompanying drawings, wherein:

Figure 1 is a side elevational view of road

2 marking equipment embodying timing mechanism constructed in accordance with this invention;

Figure 2 is a sectional view taken substantially on the plane indicated by the line 2—2 of Figure 1;

Figures 3 and 4 are respectively sectional views taken on the lines 3—3 and 4—4 of Figure 2;

Figures 5 and 6 are sectional views taken respectively on the lines 5—5 and 6—6 of Figure 3;

Figure 7 is a sectional view taken on the line 7—7 of Figure 4; and

Figure 8 is a sectional view taken on the line 8—8 of Figure 3.

As will be noted from the appended claims, the present invention concerns itself with the timing mechanism used in conjunction with road marking equipment for applying a broken line on a road surface. The timing mechanism may be satisfactorily employed with road marking equipment of various different designs and the particular equipment selected for the purpose of illustrating this invention forms no part of the present invention. Therefore, this road marking equipment is neither shown nor described in detail herein.

It will suffice to point out that the equipment functions to apply a coating on a road surface in the form of a colored binder or paint and a light reflecting material, such for example, as sand, pumice or glass beads. The paint or binder may be applied in accordance with orthodox practice by use of fluid pressure operated spray guns (not shown), and the reflecting material may be applied by the equipment shown generally in Figure 1 of the drawings.

Briefly, the above mentioned equipment comprises a carriage 10 having a frame 11 and having an axle 12 extending transversely of the frame beneath the latter. A ground engaging wheel 13 is supported on each end of the axle 12 and one of the wheels is secured to the axle so that the latter rotates as a unit with the wheel.

A hopper 14 containing a supply of reflecting material is suitably supported on the frame, and the reflecting material is conveyed by gravity to a conveyor in the form of a screw 15 having the delivery end communicating with a distributing device 16 and having a shaft 17 at the opposite end for supporting a clutch 18. The clutch is splined on the shaft 17 and is engageable with a rotatable driving member 19 freely supported on the shaft 17 beyond the clutch. The driving member 19 is operatively connected to the axle 12 of the carriage for rotation by the latter. The

clutch 18 is selectively operated by a fluid pressure device 20, and the latter is connected to a source of pneumatic pressure 21 through a control valve 22.

The above arrangement is such that when the valve 22 is opened, fluid under pressure is supplied to the device 20 through a conduit 23 and the clutch 18 is operated by the device 20 to connect the conveyor 15 to the driving member 19. As a result the reflecting material in the hopper 19 is conveyed to the distributing device 16, and the latter applies this material to the freshly painted lane which has previously been applied by suitable spray gun equipment (not shown herein). The spray gun equipment is connected to a delivery conduit 24, and the latter is also connected to the source of pneumatic pressure 21 through the valve 22. As a consequence, the valve 22 controls the application of the paint, and the reflecting material on the road surface.

The valve 22 comprises a casing 25 and a piston 26 slidably supported in a chamber 27 formed in the casing 25. The upper end of the chamber is closed by a cap 28 having a passage 29 therethrough connected to the air supply line 21 through a moisture trap 30. The valve casing 25 is formed with a discharge port 31 and the latter communicates with the conduits 23 and 24 through a fitting 32.

The valve piston 26 is formed with diametrically opposed flats 33 to enable fluid under pressure to flow from the passage 29 past the valve piston to the discharge port 31. It will also be noted that the upper end of the valve piston is formed with an annular seat 34 adapted to engage the cap 28 around the passage 29 to close communication between the air supply line 21 and the discharge port 31. The lower end of the valve piston also is formed with an annular valve seat 35 adapted to engage the bottom wall 36 of the valve chamber around a central opening 37 formed in the bottom wall. The opening 37 is of sufficient size to freely receive the upper end of an operating plunger 38. A tension spring 39 acts on the operating plunger and tends to move the valve piston 26 to its uppermost position wherein communication between the air line 21 and the discharge port 31 is closed.

The force of the spring 39 tending to move the valve piston 26 to its closed position and the pressure of the air acting on the upper end of the piston 26 tending to move the latter to its open position are regulated, so that the air pressure exceeds the spring bias by a sufficient amount to normally maintain the valve piston in its open position. In other words, in the normal position of the valve, the air under pressure in the line 21 is connected to both the distributing lines 23 and 24 to respectively operate the distributing means for the reflecting material and the paint applying device.

In many instances, it is desirable to apply a broken line on the road surface, and this is accomplished by periodically opening and closing the valve 22. In the present instance, the valve 22 is automatically operated in response to rotation of the ground engaging wheels over the road surface, and timing mechanism 40 is provided to operatively connect the valve plunger 38 to the live axle 12 of the carriage 10.

The timing mechanism 40 comprises a casing 41 suitably supported on the frame 11 and having a removable cover 42. A drive shaft 43 extends horizontally through opposite side walls of the casing, and is journaled in bearings 44. A

sprocket 45 is secured to the inner end of the drive shaft 43 and is connected to a sprocket 46 by a chain 47. The sprocket 46 is secured to the axle 12 and since the axle 12 is rotated by the ground engaging wheels, it follows that the drive shaft 43 is also rotated by the ground engaging wheels. A pulley 48 is mounted on the shaft 43 within the casing 41 and comprises two sections 49 and 50 having opposed conical surfaces. The section 49 is formed with a hub 51 spaced from the adjacent end of the bearing 44 by a thrust bearing 52, and is secured to the drive shaft 43 by a set screw 53. The section 50 of the pulley 48 has a hub 54 journaled on a bushing 55, and the latter is freely supported on the drive shaft 43. The pulley section 50 is operatively connected to the pulley section 49 for rotation as a unit with the latter by a plurality of pins 56 spaced from each other circumferentially of the shaft 43. The inner ends of the pins are secured to the pulley section 49, and the outer end portions of the pins extend freely through openings formed in the pulley section 50. Thus the pulley section 50 is rotated as a unit with the pulley section 49, but is slidable axially relative to the latter.

A coil spring 57 is supported on the shaft 43 between the pulley sections and tends to urge the pulley section 50 axially outwardly into engagement with a nut 58 having a right hand internal thread adapted to threadably engage a bushing 59. The bushing 59 is supported on the bearing 44 and is provided with a threaded head portion 60 which extends through an opening in the outer wall of the casing. A lock nut 61 is threaded on the head 60 and serves to secure the bushing 59 to the casing. A thrust bearing 62 is slidably supported on the drive shaft 43 between the outer end of the hub 54 and the inner end of the bushing 59. The above arrangement is such that rotation of the nut 58 relative to the threaded bushing 59 in one direction moves the pulley section 50 axially toward the pulley section 49 and movement of the nut 58 in the opposite direction enables the spring 57 to move the pulley section 50 in a direction away from the pulley section 49.

A driven shaft 63 is journaled in the casing with its axis extending parallel to the axis of the drive shaft 43 and a pulley 64 is mounted on the driven shaft directly opposite the pulley 48. The pulley 64 is identical to the pulley 48 in that it is formed of two sections 65 and 66 having opposed conical surfaces. The section 65 is secured to the driven shaft 63 by a set screw 67, and the hub portion 68 of the section 66 is journaled on a bushing 69, similar to the bushing 55. A plurality of pins 70 are secured to the pulley section 65 in spaced relation to each other circumferentially of the axis of the pulley, and extend inwardly through openings formed in the pulley section 66. Thus the pulley section 66 is rotated as a unit with the pulley section 65 and is also movable axially relative to the pulley section 65.

A nut 71 having an internal left hand thread is threadably supported on a bushing 72, and the latter is supported on a bearing 73 for the outer end of the driven shaft. The outer end of the bushing 72 is formed with an enlarged thread head 74, and a lock nut 75 is provided for securing the bushing to the casing. A thrust bearing 76 is slidably supported on the driven shaft 63 between the outer end of the hub 68 and the inner end of the bushing 72. A coil spring 77 is provided on the driven shaft 63 between the pulley sections and normally urges the pulley section

66 axially outwardly into bearing engagement with the thrust bearing 76.

A V-belt 78 is reeved around the pulleys 48 and 64 for driving the driven shaft 63 from the drive shaft 43. The speed at which the driven shaft 63 is rotated from the drive shaft 43 may be varied by increasing and decreasing the effective diameters of the pulleys 48 and 64. In the present instance the diameter of one pulley is increased while the diameter of the other pulley is decreased by providing means for simultaneously rotating the nuts 58 and 71. As shown particularly in Figure 4 of the drawings, it will be noted that a pair of collars 79 and 80 are respectively clamped to the nuts 58 and 71. The collars are fashioned with upwardly extending projections 81, and these projections are connected together by an adjustable link 82. Thus rocking movement of one collar effects a corresponding rocking movement of the other collar and adjusting means 83 is provided for this purpose. The adjusting means 83 comprises a rod 84 having the inner end pivotally connected to the extension 81 on the collar 79 and having the outer end projecting through an opening 85 in one end wall of the casing. The outer end of the rod 84 is threaded and an adjusting nut 86 threadably engages the rod beyond the adjacent end wall of the casing. The adjusting nut 86 is normally maintained in bearing engagement with the adjacent end wall 30 of the casing by a coil spring 87 surrounding the rod with the inner end engaging an abutment 88 and with the outer end engaging the inner surface of the adjacent wall of the casing. The above arrangement is such that rotation of the nut 86 in opposite directions effects a simultaneous rocking movement of the collars 79 and 80 in the same directions. Inasmuch as the collars 79 and 80 are respectively secured to the nuts 58 and 71, and since the latter are provided with left and right hand threads, it follows that the effective diameter of one of the pulleys is increased and the effective diameter of the other pulley is decreased to vary the speed of rotation of the driven shaft 63 accordingly. The type of variable speed transmission mechanism above described is generally designated as the "Reeves" drive.

The driven shaft 63 operates the valve 22 and for accomplishing this result, a cam 90 is secured to the driven shaft 63 at the inner side of the pulley 64. As shown particularly in Figure 3 of the drawings the cam 90 has an eccentric circular peripheral surface and the action of the cam 90 is transmitted to the valve plunger 38 by a laminated spring third class lever 91 engageable with the periphery of the cam intermediate the ends thereof. One end of the spring lever 91 is anchored to an abutment 92 and the other end of the spring extends between a support 93 and the lower end of the valve operating plunger 38. The valve is secured to the cover 42 of the casing 41 by a bracket 94 and the valve plunger extends through an opening formed in the cover to a position in operative relation to the spring lever 91.

In Figure 3 of the drawing, the valve 22 is in its open position and air under pressure is admitted through the valve to the distributing conduits 23 and 24. However, continued rotation of the cam 90 in the direction of the arrow in Figure 3 moves the plunger 38 in an upward direction through the spring lever 91 and closes the valve 22. The design of the cam 90 is such that the valve 22 is held in its closed position for approximately 180° of rotation of the cam, where-

upon continued rotation of the cam throughout the remaining 180° of rotation permits opening of the valve 22 by the pressure in the supply line 21. Thus, the length of the valve opening and closing cycle depends upon the speed or rotation of the driven shaft 63 by the drive shaft 43. As stated above, this cycle may be varied by manipulating the adjusting nut 86 to change the ratio between the driving and driven shafts. Consequently, a broken line may be applied to the road surface having painted and unpainted portions of varying lengths. It is also desirable to vary the relative lengths of the painted and unpainted portions of the line and this may be accomplished by varying the elevation of the abutment 92. Referring again to Figure 3 of the drawings, it will be noted that the abutment 92 is secured to the lower end of a vertical rod 95 having the upper end portion extending through an opening 96 in the cover 42 of the casing. A bushing 97 is threaded in the opening 96 and is axially bored to receive the rod 95. The upper end of the rod is threaded and a nut 98 is threadably mounted thereon. The nut 98 is normally urged into engagement with the upper end of the bushing 97 by a coil spring 99 surrounding the rod 95. The lower end of the spring 99 is seated on the abutment 92 and the upper end of the spring 99 engages the bushing 97. By adjusting the nut 98, the elevation of the spring lever 91 relative to the cam 90 is varied, and the interval of engagement of the cam with the spring is likewise varied. As a result the period during which the valve 22 remains open may be varied in relation to the period during which the valve remains closed, so that the painted portions of the broken lines may be altered in length to suit specified conditions.

It is also desirable under certain conditions to enable starting the painted portion of the line at a preselected zone on the road surface. This is particularly true when previously painted broken lines are retraced. The above setting may be accomplished without interfering with the ground engaging wheels of the carriage 10 by releasing the tension on the belt 78 and rotating the driven shaft 63. In detail, it will be noted that the belt is normally tensioned by a device 101 comprising a U-shaped member 102 having the base portion hinged to one end of the casing by a bracket 103 and having the leg portions 104 extending inwardly from the wall aforesaid of the casing above the belt 78. A roller 105 is journaled on the free ends of the leg portions 104 and has a bearing engagement with the top surface of the belt at a point between the pulleys 48 and 64. The roller 105 is normally urged into frictional contact with the belt 78 by a vertical plunger 106 having a head portion at the lower end engaging a cross rod 107 extending between the free end portions of the legs 104 and having a shank 108 extending upwardly through an opening in the cover 42 of the casing. A hand knob 109 is secured to the upper end of the shank and a spring 110 normally urges the plunger downwardly into engagement with the cross rod 107. Thus, when it is desired to adjust the angular position of the cam 90 to vary the interval of opening of the valve 22, the plunger is moved upwardly against the action of the spring 110 to release the tension on the belt 78, and the driven shaft 63 is rotated the required amount by a hand wheel 112. The hand wheel is secured to the outer end of the driven shaft where it may be readily accessible for adjustment purposes.

What I claim as my invention is:

1. Road marking equipment comprising a vehicle having a ground engaging wheel, fluid pressure operated coating applying mechanism having a source of fluid under pressure, a valve controlling the flow of fluid under pressure to the coating applying mechanism, a rotatable cam for periodically opening and closing the valve, and variable ratio driving means connecting said cam to the ground engaging wheel.

2. Road marking equipment comprising a vehicle having a ground engaging wheel, fluid pressure operated coating applying mechanism having a source of fluid under pressure, a valve controlling the flow of fluid under pressure to the coating applying mechanism, a rotatable cam for periodically opening and closing the valve, variable ratio driving means operatively connecting the cam to the ground engaging wheel, and means for disconnecting said cam from said driving means, and means for adjusting the angular position of the disconnected cam relative to the valve independently of said driving means.

3. Road marking equipment comprising a vehicle having a ground engaging wheel, fluid pressure operated coating applying mechanism having a source of fluid under pressure, a valve controlling the flow of fluid under pressure to the coating applying mechanism, a cam rotatable in response to rotation of the ground engaging wheel over the road surface, means actuated by said cam for periodically opening and closing the valve, and adjustable means for varying the speed of rotation of said cam relative to said ground engaging wheel.

4. Road marking equipment comprising a vehicle having a ground engaging wheel, fluid pressure operated coating applying mechanism having a source of fluid under pressure, a valve controlling the flow of fluid under pressure to the coating applying mechanism, a rotatable cam operatively connected to the ground engaging wheel for rotation by the latter and having means for periodically opening and closing the valve, adjustable means for varying the speed of rotation of the cam by the ground engaging wheel, and adjustable means between the cam and valve for varying the open and closed periods of the valve.

5. Road marking equipment comprising a vehicle having a ground engaging wheel, fluid pressure operated coating applying mechanism having a source of fluid under pressure, a valve controlling the flow of fluid under pressure to the coating applying mechanism, a rotatable cam operatively connected to the ground engaging wheel for rotation by the latter and having means for periodically opening and closing the valve, adjustable means for varying the speed of rotation of the cam by the ground engaging wheel, adjustable means for varying the open and closed periods of the valve, and means for adjusting the angular position of the cam relative to the valve independently of the ground engaging wheel.

6. Road marking equipment comprising a vehicle having a ground engaging wheel, fluid pressure operated coating applying mechanism having a source of fluid under pressure, a valve

means controlling the flow of fluid biased to open, a rotatable cam driven by said ground engaging wheel for periodically closing said valve, a lever intermediate said cam and valve means, and means for moving the fulcrum of said lever towards or from said cam to vary the ratio between the opened and closed periods of said valve.

7. Road marking equipment comprising a vehicle having a ground engaging wheel, fluid pressure operated coating applying mechanism having a source of fluid under pressure, a valve means controlling the flow of fluid biased to open, a rotatable cam driven by said ground engaging wheel for periodically closing said valve, a resilient lever intermediate said cam and valve means, and means for adjusting the fulcrum of said lever towards or from said cam to vary the ratio of the opened and closed periods of said valve.

8. Road marking equipment comprising a vehicle having a ground engaging wheel, fluid pressure operated coating applying mechanism having a source of fluid under pressure, a valve controlling the flow of fluid under pressure to the coating applying mechanism, a rotatable cam for periodically opening and closing said valve, and a variable speed transmission of the "Reeves" type intermediate said ground engaging wheel and said cam.

9. Road marking equipment comprising a vehicle having a ground engaging wheel, fluid pressure operated coating applying mechanism having a source of fluid under pressure, a valve controlling the flow of fluid under pressure to the coating applying mechanism, a rotatable cam for periodically opening and closing said valve, a variable speed transmission of the "Reeves" type including a belt and belt tightener intermediate said ground engaging wheel and said cam, and means for adjusting said belt tightener to free said cam and permit independent rotational adjustment thereof to alter the angular position of the same relative to said valve.

10. Road marking equipment comprising a vehicle having a ground engaging wheel, fluid pressure operated coating applying mechanism having a source of fluid under pressure, a valve controlling the flow of fluid under pressure to the coating applying mechanism said valve being biased to open a rotatable eccentric circular cam for periodically closing said valve, a resilient lever intermediate said cam and valve, means for adjusting the fulcrum of said lever towards or from said cam to change the ratio between the opened and closed periods of said valve, a variable ratio drive means connecting said cam to the ground engaging wheel, and means for freeing said cam from said driving means to permit angular adjustment thereof relative to said valve.
